DESIGN FOR A DRAWER PULL

Odin A. Westgaard, Los Angeles, Calif., assignor
to Modern Plastics Company, Los Angeles,
Calif., a corporation of California

Application November 13, 1939, Serial No. 88,224

Term of patent 7 years

To all whom it may concern:

Be it known that I, Odin A. Westgaard, a citizen of the United States, residing at Los Angeles, in the county of Los Angeles and State of California, have invented a new, original, and ornamental Design for a Drawer Pull, of which the following is a specification, reference being had to the accompanying drawing, forming part thereof.

Fig. 1 is a plan view of the drawer pull embodying my new design; Fig. 2 is a view in front elevation of the same taken in the direction of the

arrow 2 upon Fig. 1; Fig. 3 is a rear view in elevation of the same taken in the direction of the arrow 3 upon Fig. 1; Fig. 4 is a sectional view taken substantially upon the line 4—4 upon Fig. 1.

The drawer pull embodying my new design has the two parts forming the same formed of contrastingly colored materials.

I claim:

The ornamental design for a drawer pull, as shown and described.

ODIN A. WESTGAARD.
